Fig. 3.

To all whom it may concern:

Be it known that we, Mack R. Fields, George R. Ryan, and Roland A. McMinn, citizens of the United States, and a resident of Libertyville, in the county of Lake and State of Illinois; a resident of Waukegan, in the county of Lake and State of Illinois; and a resident of Waukegan, in the county of Lake and State of Illinois, respectively, have invented a new, original, and ornamental Design for a Hypodermic Syringe, of which the following is a specification, reference being had to the accompanying drawing, forming a part thereof.

In the accompanying drawing:

Figure 1 is a perspective view of a hypodermic syringe embodying our new design.

Figure 2 is a plan view of the same device.

Figure 3 is a perspective view of the same device shown in Figure 1 with the actuating means removed for con-

Figure 4 is a perspective view taken from the opposite end of Figure 3.

We claim:

The ornamental design for a hypodermic syringe, substantially as shown.
